PAINT OR PIGMENT SELECTING, MEASURING,
AND DISPENSING MACHINE

Raymond Spilman, Bronxville, N. Y., Henry Sherk Jones,
Stamford, Conn., and Charles Francis Stephenson, New
York, N. Y., assignors to Standard-Toch Chemicals,
Inc., Staten Island, N. Y., a corporation of New York

Application October 23, 1953, Serial No. 27,298

Term of patent 14 years

(Cl. D52—2)

To all whom it may concern:

Be it known that we, Raymond Spilman, Henry Sherk Jones, and Charles F. Stephenson, all citizens of the United States of America, residing at 840 Bronx River Road, Bronxville, Westchester County, New York, 242 Sylvan Knoll Road, Stamford, Connecticut, and 277 West 12th Street, New York city, New York, respectively, have invented a new, original, and ornamental Design for a Paint or Pigment Selecting, Measuring, and Dispensing Machine, of which the following is a specification, reference being had to the accompanying drawing, forming part thereof.

In the drawing:

Figs. 1 and 2 are perspective views of the front and

rear of a paint or pigment selecting, measuring, and dispensing machine, showing our new design.

We claim:

The ornamental design for a paint or pigment selecting, measuring, and dispensing machine, substantially as shown.
